ENGINE STARTER DRIVE FOR INTERNAL COMBUSTION ENGINES

James J. Digby and Maurice P. Whitney, Elmira, N.Y., assignors to Bendix Aviation Corporation, Elmira Heights, N.Y., a corporation of Delaware

Application May 3, 1955, Serial No. 505,665

4 Claims. (Cl. 74—7)

The present invention relates to an engine starter drive for internal combustion engines, and more particularly to the so-called "barrel type" in which the drive pinion is actuated from the control nut through an intermediary in the form of a barrel member.

In the barrel types of starter drive as shown for instance in the patents to Buxton 2,609,695 issued September 9, 1952, and Strozinski 2,673,467 issued March 30, 1954, various means have been used to anchor the control nut in the barrel in such manner as to resist the shock loads both torsionally and axially to which the drives are subjected in use.

Such means have commonly included a plurality of lugs projecting radially from the periphery of the control nut into slots formed in the barrel. The control nut is customarily made from solid bar stock of a diameter to include said lugs, the body of the control nut being turned down and milled in such manner as to leave the lugs projecting therefrom. Since the cost of bar steel increases rapidly with its diameter, and the above operations involve removing a substantial portion of the original stock, it is obvious that the control nut so formed is a comparatively expensive part as respects both material and fabrication. On the other hand, the use of keying elements formed separately and mounted on the control nut has not proved a satisfactory solution of the problem.

It is an object of the present invention to provide a novel engine starter drive which is well adapted to withstand the forces encountered in use and is economical to manufacture as respects material, fabrication and assembly.

It is another object to provide such a device in which the parts may be readily disassembled for selective replacement.

Further objects and advantages will be apparent from the following description taken in connection with the accompanying drawings, in which:

Fig. 1 is a side elevation partly broken away and in section of a preferred embodiment of the invention;

Fig. 2 is an end view of the control nut;

Fig. 3 is a section of the control nut on the line 3—3 of Fig. 2;

Fig. 4 is an end view of the barrel member;

Fig. 5 is a section of the barrel member on the line 5—5 of Fig. 4;

Fig. 6 is a side elevation partly broken away and in section of a second embodiment of the invention;

Fig. 7 is an end view of the barrel member shown in Fig. 6;

Fig. 8 is a section of the barrel member on the line 8—8 of Fig. 7;

Fig. 9 is an end view of a modified form of barrel member with the control nut anchored therein; and

Fig. 10 is a section taken on the line 10—10 of Fig. 9.

In Fig. 1 of the drawing, there is illustrated a power shaft 1 on which a sleeve 2 is fixed in any suitable manner as indicated at 3. The sleeve 2 is provided with a smooth

2

reduced portion 4 providing a shoulder 5. A screw shaft 6 is slidably journaled on said reduced portion 4.

Means for yieldably actuating the screw shaft 6 from the sleeve 2 is provided comprising an anchor plate 7 non-rotatably mounted on the sleeve, a second anchor plate 8 non-rotatably mounted on a driving overrunning clutch member 9 slidably journaled on the smooth portion 4 of the sleeve, and a coiled drive spring 11 having out-turned ends 12 and 13 entering corresponding slots in the anchor plates 7, 8.

10 The clutch member 9 is provided with teeth 14 adapted to cooperate with similar teeth 15 on the adjacent end of the screw shaft 6. Stop ring 16 seated in a groove in the sleeve member 4 occupies a counterbore in the clutch member 9 and serves to limit its longitudinal movement to the right and thereby places the drive spring 11 under slight initial compression.

A pinion 17 is slidably journaled on the power shaft 1 for movement into and out of mesh with a gear 18 of the engine to be started. Means for actuating the pinion 17 from the screw shaft 6 is provided comprising a control nut 19 and a barrel member 21 fixedly mounted at one end on the pinion 17 as indicated at 22, and at its other end rigidly connected with the control nut 19 in a manner to be more fully described.

30 The idle position of the control nut on the screw shaft is defined by the ends 23 of the threads of the screw shaft while the meshed position of the control nut and pinion assembly is defined by an abutment ring 24 fixed on the end of sleeve 2 by means of a lock ring 25 seated on a groove in said sleeve. A spring washer 26 located between the end of the screw shaft and the abutment ring 24 normally holds the teeth 15 of the screw shaft in engagement with the teeth 14 of the clutch member 9, a thrust washer 27 being preferably interposed between the screw shaft and the abutment ring.

35 In accordance with the present invention the control nut 19 has a sliding fit within the end of the barrel member 21, and is provided with a plurality of axially extending peripheral channels or notches 28 (Fig. 2). The barrel member is provided with a corresponding plurality of inwardly extending arms 29 (Fig. 5) which are partially sheared and pressed inwardly and formed with portions 31 adapted to fit in the channels 28 of the control nut.

40 The arms 29 are provided with shoulders 32 acting as abutments for the control nut 19, and a lock ring 33 (Fig. 1) seated in a groove 34 in the free end of the barrel member holds the control nut against said shoulders.

45 In order to prevent the pinion and barrel assembly from drifting away from idle position, the threads of the screw shaft 6 are reduced in diameter adjacent the idle position of the control nut to form inclined shoulders 35; and one or more spring pressed detents 36 are mounted in the control nut in position to engage said shoulders as the control nut moves away from idle position and thereby yieldingly resist such movement.

50 In the operation of this embodiment of the invention, rotation of power shaft 1 by the starting motor, not illustrated, is transmitted through the sleeve 2, the yielding driving connection including the spring 11, and the overrunning clutch member 9 to the screw shaft 6, thereby causing the control nut 19 to move the pinion 17 into mesh with the engine gear 18 until the meshing movement is arrested by the abutment ring 24, after which the screw shaft 6 is forced backward, compressing the spring 11 until the backward movement of the clutch member 9 is arrested by the shoulder 5 of sleeve 2. The pinion 17 is then rotated to crank the engine. When the engine fires, the overrunning action causes the pinion

assembly to be returned to idle position where it is maintained by means of anti-drift detents 36; overrunning of the pinion assembly and screw shaft being permitted by the clutch connection 14, 15.

In Figs. 6 to 8 there is illustrated a starter drive similar to that shown in Figs. 1 to 5 inclusive but embodying a modified anchorage of the control nut to the barrel. As there shown, the control nut 19' is formed similarly to the control nut 19 in the first embodiment of the invention, and is provided with notches 28'. The barrel member 21' is formed with inwardly extended bars 40 which are sheared and pressed inwardly from the body of the barrel but which are left attached to the barrel at both ends as indicated at 41, 42 (Fig. 8). The bars 40 are of such width as to snugly fit within the notches 28' of the control nut 19'. Meshing movement of the control nut is transmitted to the barrel member by means of shoulders 43 which are partially sheared and pressed inwardly from the body of the barrel in position to abut against the side of the control nut 19'. The control nut is held in the barrel in engagement with the shoulders 43 by means of lock ring 33' seated in a groove 34' in the free end of the barrel.

The remaining parts of this embodiment of the drive are the same as those illustrated in the first embodiment and are similarly numbered, and the operation of this embodiment is the same as previously described.

In Figs. 9 and 10 of the drawing there is illustrated a slightly modified form of barrel member 21'. As there shown, instead of forming the groove 34' for reception of the lock ring 33' as in Figs. 6 and 7, in this case the lock ring 33'' fits slidably in the open end of the barrel, and strips from the rim of the barrel at angularly spaced points are sheared and bowed inwardly as indicated at 44 (Fig. 9) to retain the lock ring in place. The bowed strips 44 are preferably aligned with the keying bars 40, so that when the lock ring 33'' is removed, the control nut 19' can be slid out of the barrel.

Although certain structure has been shown and described in detail, it will be understood that other embodiments are possible and changes may be made in the design and arrangement of the parts without departing from the spirit of the invention.

We claim:

1. In an engine starter drive a power shaft, a sleeve

fixed thereon, a screw shaft slidably journaled on the sleeve, a yielding driving connection from the sleeve to the screw shaft, a pinion slidably journaled on the power shaft, and means for actuating the pinion from the screw shaft including a cylindrical barrel member fixed at one end to the pinion, its other end being open, a control nut threaded on the screw shaft slidably fitting in the open end of the barrel, said control nut having a plurality of axially extending peripheral channels with flat, parallel, substantially radial sides; said barrel having a corresponding number of integral rectangular axially extending keying bars off-set inwardly from the body of the barrel received in and tightly fitting said channels; the barrel also having a plurality of circumferentially arranged inwardly extending integral shoulders forming a thrust bearing for the control nut, and means for holding the control nut against said thrust bearing including a lock ring anchored in the barrel in abutting relation to the control nut.

2. A starter drive as set forth in claim 1 in which the intermediate portions of the keying bars separated from the barrel and displaced inwardly to engage in the channels of the control nut, the ends of the bars remaining integral with the body of the barrel.

3. A starter drive as set forth in claim 2 in which the means for preventing relative longitudinal movement of the control nut and barrel includes a plurality of abutments partially separated and displaced inwardly from the body of the barrel, and having flat terminal surfaces forming stops for the control nut in the barrel.

4. A starter drive as set forth in claim 2 in which the means for preventing relative longitudinal movement of the control nut and barrel includes a thrust ring seated in the open end of the barrel against said control nut; the rim of the barrel having a plurality of arcuate strips displaced and bowed inwardly to engage the thrust ring and confine it in the barrel.
